UNITED STATES PATENT OFFICE.

DAVID A. EBINGER, OF COLUMBUS, OHIO.

DESIGN FOR A URINAL.

45,330.

Specification for Design.

Patented Mar. 3, 1914.

Application filed December 26, 1913. Serial No. 808,917. Term of patent 14 years.

To all whom it may concern:

Be it known that I, DAVID A. EBINGER, a citizen of the United States, residing at Columbus, in the county of Franklin and State of Ohio, have invented a new, original, and ornamental Design for Urinals, of which the following is a specification, reference being had to the accompanying drawing, forming part thereof.

The figure is a perspective view of a urinal, showing my new design.

I claim:

The ornamental design for a urinal, as shown.

DAVID A. EBINGER.

Witnesses:

WALTER E. L. BOCK,
A. L. PHELPS.
